UNITED STATES PATENT OFFICE.

FRIEDRICH MÜNZ, OF STUTTGART, GERMANY.

SPINNING SPINDLE.

Application filed February 19, 1920, Serial No. 359,962. Renewed March 3, 1922. Serial No. 540,922.

(GRANTED UNDER THE PROVISIONS OF THE ACT OF MARCH 3, 1921, 41 STAT. L., 1313.)

To all whom it may concern:

Be it known that I, FRIEDRICH MÜNZ, residing at Stuttgart, Blumenstrasse 27, Germany, have invented certain new and useful Improvements in Spinning Spindles (for which I have filed an application in Germany Feb. 12, 1919), of which the following is a specification.

The present invention relates to spinning spindles with ball bearings and a distinguishing feature of the invention is that only a single ball bearing is used between the spindle and the tubular body thereof, the bearing being surrounded by the driving pulley. Another feature of the invention is that the bottom end of the spindle is pointed and rests in an open cone-shaped cavity or seat formed in the upper end of a swinging support or prop normally held vertical by laterally disposed springs, the length of the support being such that when the spindle is deflected no gap or play is produced beneath the seat and the bearing end of the spindle. An advantage gained by this arrangement is that the bottom end of the spindle may deflect freely in all directions without giving rise to jamming of the supporting bearing, and besides smooth running of the spindle is obtained because the swinging support keeps the spindle securely propped up no matter what position it might swing into.

Instead of lubricating the spindle with grease a circulating oil lubrication may be provided.

Provision is made for a circulating oil lubrication according to the invention by arranging the swinging support and its springs inside a perforated threaded cylindrical shell or barrel, which, by means of its thread and a threaded ring can be precisely set with respect to the end of the spindle, and over which an outside shell is pushed which serves as an oil reservoir. By this arrangement the oil is caused to enter through the holes of the first mentioned shell and to wash around the end of the spindle so that it and the step bearing are permanently immersed in oil. The spindle tapers from the position where its ball bearing is situated down to its bottom end and the rapid rotation of the conical spindle gives rise to a sucking action which causes the oil at the bottom end of the spindle to

climb up to point of maximum diameter of 55 the spindle, i. e., up to the ball bearing, which is thus copiously lubricated. From the ball bearing the oil creeps along the inner walls of the spindle body and back into the shell. Any particles of oil that might 60 pass up beyond the ball bearing may be caught up and returned to the ball bearing by some suitable device such as an annular cup formed around the spindle by a ring-shaped extension, so that no oil is lost and a permanent 65 lubrication is secured. The same effect may also be obtained when the swinging support is suspended instead of being stood up on end. The suspended arrangement comes into consideration when the space at the 70 bottom of the spindle is limited and hence a shorter construction is desired.

Three constructional forms of the new spinning spindle are shown in the drawing in which

Fig. 1 is a vertical section of a spindle with a greased ball bearing,

Fig. 2 shows a horizontal or cross section of Fig. 1 on the line A—B,

Fig. 3 illustrates a second constructional 80 form equipped with a standing swinging support and a circulating oil lubrication and

Fig. 4 represents the third constructional form with a circulating oil lubrication and 85 a hanging swinging support.

Referring to Fig. 1 a ball race is ground into the tempered spindle *b* at the height of the driving pulley *c* of the whirl *d*. The balls *k* are kept in position by an outer ball 90 bearing ring *m* which is held in turn by a ring *n*, in the upper end of the tubular body of the spindle. The lower end *e* of the spindle *b* which tapers down to a point is borne in a conical bearing cup *f* held up by 95 a swinging support or prop *g*. The prop is kept in its middle position by lateral springs *h* arranged in opposed openings in the barrel and its lower pointed end is seated in a cup formed in a threaded bushing *i*, 100 mounted in the lower end of the spindle body. By means of the threaded bushing *i* the swinging support *g* can be raised or lowered in the proper position with respect to the end *e* of the spindle. The socket receiving the spindle is of sufficient depth to retain the said spindle therein at all 105 times. Hence no gap can be formed be-

tween the end of the spindle and the bearing cup *f* when the spindle deflects, so that play is prevented.

The cushioning of the end *e* of the spindle 5 between springs is adopted in order to ease the knocks and irregularities occurring during winding, thereby securing smooth and uniform running. The threaded bushing is 10 preferably made in the form of a Stauffer lubricator.

As shown in Fig. 3 the swinging prop *g* and its springs *h* are arranged in a perforated threaded sleeve or barrel *o* which is closed at the bottom and whose position relative to the end of the spindle *e* may be precisely adjusted by means of the thread *p* 15 and the threaded ring *q*. *r* is an outside shell or oil reservoir which is slipped over the sleeve *o* and provided with a thread or 20 any fastening or sealing means which enables the reservoir to be easily detached. *f* is the step bearing, *s* the body of the spindle and *k* the ball bearing. The spindle body *s* is provided with a ring-shaped extension *t* that forms a small annular cup *u* 25 in which any particles of oil are caught up that might rise above the ball bearing.

In the modification shewn in Fig. 4 the swinging support *g* is suspended, the upper 30 part of the suspension member being formed in the shape of a ball surface that is seated in the upper part of the sleeve *o*. This sleeve *o* is also arranged to be adjusted 35 with respect to the end *e* of the spindle by means of the thread *p* and the threaded ring *q*.

It will be obvious that many changes 40 and modifications can be made without departing from the scope and spirit of the invention.

I claim:

1. In a spinning device, in combination with a stationary tubular body, a ball bearing mounted in the upper end thereof, a deflectable spindle arranged through the 45 body and contacting with the bearing approximately medially of its height, a supporting prop having a bearing cup in its upper end for receiving the lower end of the spindle, a threaded perforated barrel 50 supporting the prop and adjustably connected to the lower end of the body so as to support the prop with respect to the body and the spindle, laterally disposed springs within the barrel for normally holding the 55 prop in a vertical position, and an oil reservoir associated with the perforated barrel.

2. The combination with a spinning device of an oil reservoir, a threaded perforated barrel arranged in the said oil reservoir, a support in the said barrel, lateral springs holding the said support, a bearing cup in the said support, a deflectable vertical spindle with its bottom end resting in 60 the said bearing cup, a driving pulley attached to the said spindle, a ball bearing arranged approximately mid-height the spindle and surrounded by the driving pulley, a hollow body arranged around the said 65 spindle and provided with a thread into which the thread of the said perforated barrel is screwed, whereby the position of the bearing cup relative to the bottom end of the spindle may be adjusted, and a ring-shaped extension on the hollow body reaching up beyond the ball bearing so as to 70 form an annular oil cup.

In testimony whereof I affix my signature.
FRIEDRICH MÜNZ.
